UNITED STATES PATENT OFFICE.

ERASTUS E. PIERCE AND LEWIS W. NEWTON, OF NEW BRIGHTON, PENNSYLVANIA, ASSIGNORS TO THE STANDARD HORSE NAIL COMPANY, OF PENNSYLVANIA.

MACHINE FOR FORGING POINTS OF HORSESHOE-NAILS.

SPECIFICATION forming part of Letters Patent No. 670,622, dated March 26, 1901.

Application filed June 19, 1899. Serial No. 721,055. (No model.)

To all whom it may concern:

Be it known that we, ERASTUS E. PIERCE and LEWIS W. NEWTON, citizens of the United States of America, and residents of 5 New Brighton, county of Beaver, and State of Pennsylvania, have invented certain new and useful Improvements in Machines for Forging the Points of Horseshoe-Nails, of which the following is a specification.

10 Our invention, generally stated, relates to a machine for forging the points of horseshoe-nails.

The full particulars of the invention are set forth in the subjoined specification and 15 claims, together with some of the advantages thereof.

In the accompanying drawings, which make part of this specification, Figure 1 is a partial plan view of a machine embodying our invention and showing the cap-plate A with its various housings, lugs, and slideways with their slides and the levers for working them, with their inner ends engaged by the spool B, also showing the location of the cutting or 20 clipping devices with their chutes a a attached and their operating-levers b b engaged by the spool B, and the levers c, carrying the facing and beveling dies, their inner ends, which engage the spool C being hidden by the 25 spool B. A part of the main frame, a part of the turret-operating mechanism, and the shaft L are also shown. Fig. 2 is a side elevation of the machine with some parts removed and parts of the cap-plate A broken 30 away, so as to show one of the levers c, with a beveling-die, and one of the levers d, which operate the slides e, and the levers f f, attached thereto, which carry the edging-dies. A pair of the levers f f are shown in position at top center, Fig. 2. Fig. 3 is a plan view, all parts above the turret being removed. One half the turret is provided with vises and the other half shows the sockets for the vise-blocks and in dotted lines the channels on the under side of the turret, by means 35 of which it is alternately moved and locked. Fig. 4 is a rear elevation of a part of the machine. Fig. 5 is a plan view showing the circular supporting-base E, its flange g, its inwardly-projecting arms g' g' g', cylinder g²

and flange g³, and a portion of the head J, with the cam-plate h for closing the vises attached. The cam i for opening the vises and the cam i' to prevent the too sudden movement of the vise-levers are also shown carried by the plate i², one end of which is secured to the under side of the flange g. Fig. 6 is an elevation, partly in section, showing one of the vises and its supporting-block, a part of the head J with the cam-plate h attached, and the slideway E, turret D, and spools B C. Fig. 7 is a side elevation showing a part of the mechanism for reciprocating the blank-holder. Figs. 8 and 9 are side and front elevations of one of the pairs of 65 cutters and their holding and actuating mechanism. Figs. 10 and 11 are similar views of a pair of facing-dies and connected parts. Fig. 12 is a side elevation of an anvil and beveling-die and their holding and actuating 70 mechanism as used in the later stages of forming the point, with the cap-plate A in section. Figs. 13 and 14 are front elevation and side sectional elevation of the first pair of edging-dies with their holding and actuating mechanism. Fig. 15 is a perspective of half of one of a modified form of one of the edging-dies, the figure being broken away. Figs. 16 and 17 are similar views showing the construction in connection with the remaining 75 80 edging-dies. Fig. 18 is an end view illustrating one of the vises. Fig. 19 is a section on lines 19 19 of Fig. 18. Fig. 20 is a side view, in part section, of the blank-holder mounted on the rock-shaft L. Fig. 21 is a part front 85 view of same. Fig. 22 is a plan view of one of the cutters. Figs. 23 to 33 are views illustrating the blank and progressive formation of the nail-point by the action of the dies and cutters. 90

Before describing the construction of the machine as a whole we will set forth the operations to be performed on the end of the shank of a blank in order to point the same and will then refer in detail to the means by 95 which the operating-dies and other parts are actuated, inasmuch as with proper dies various different actuating means may be employed.

Each blank Z, Fig. 23, is somewhat longer 100

than the nail to be formed and is presented successively between dies which act on the side edges and which we term "edging-dies" and dies which act on the opposite faces and 5 which we term "facing-dies" when they are substantially parallel and "beveling-dies" when one is at an angle to the other.

The blank is first acted upon between two edging-dies $F^3 F^3$, which indent it, as shown 10 in Fig. 24, and this has also the effect of upsetting it to increase its thickness adjacent to the indentations, as shown in Fig. 25. The facing-dies $H' H^2$ then reduce the thickened portion as the blank is compressed between 15 them, and another pair of edging-dies now act to further indent the blank, as shown in Fig. 26, upsetting it, as indicated in Fig. 27, after which it is again subjected to pressure between another pair of facing-dies and again 20 indented by edging-dies, as shown in Fig. 28, of which there may be any desired number. These repeated side and face pressures not only indent and compress the shank, but further elongate it, and the end is then cut off 25 beyond the narrowest part, as indicated in Figs. 28 and 29. The end of the blank is now subjected to the action of the beveling-dies $H^3 H^4$, the latter having the face against which the back of the blank bears parallel thereto, 30 while the face of the die H^4 , which acts on the front of the blank, is at an angle to the working face of the die H^3 , so that pressure between the two imparts a bevel to the front of the shank at the end, as indicated in Figs. 35 30 and 31. The blank is now again operated on by edging-dies $F^3 F^3$, as indicated in Fig. 32, and as it is spread or upset thereby is again subjected to the actions of beveling-dies, these operations being repeated any de- 40 sired number of times, and as the successive edge and face pressures draw out the metal the surplus is sheared off and the point finally finished by a number of successive alternate actions of edge and beveling dies. It will be 45 seen that the point is thus forged cold by a succession of operations alternately on the side edges and faces, gradually drawing it out from the blank, condensing and hardening the metal, and tapering and beveling the same by 50 actions closely approximating those of a workman in forging the point of a nail-blank by hand between a hammer and anvil, turning the blank to present successively the faces and the edges to be acted on. It will be evi- 55 dent, however, that by the operations de- scribed, when performed in an organized ma- chine, the results are superior to hand-work in that the articles produced are all uniform in character and far better finished.

60 Having thus set forth the operations upon the blank to point the same, we will now de- scribe one construction of mechanism by means of which they can be performed.

The nail-blank, clamped by suitable clamps 65 m at the end of a vibrating arm m' , Fig. 2, is first carried head first between suitable face-finishing rolls $m^2 m^3$. These parts may be

like those set forth in Letters Patent to E. E. Pierce, Nos. 363,417 and 379,413, and as they have no necessary connection with this in- 70 vention herein claimed need not be further referred to or described. On passing from the roller-dies $m^2 m^3$ the head of the blank is forced between two springs-arms $j j$, Figs. 20 and 21, of a holder J , Fig. 2, which holder first 75 occupies a horizontal position to receive the head of the blank and then turns to a vertical position, and the head of the holder (which holder is in two parts) then rises and carries the blank into position to be gripped by a 80 vise F , as hereinafter described. The said vise F is on an intermittently-rotating ring G and carries the blank in a circle to positions to be operated on successively by the various edging-dies, facing and beveling dies, 85 and cutters. The general arrangement of these parts for operating on the blank carried by the vise is illustrated in Fig. 1, where the positions of the edging-dies is illustrated at 2 2 2, &c., that of the facing-dies at 3 3 3, &c., 90 that of the beveling-dies at 4 4 4, &c., and that of the cutters at 5 5, the finished nail being discharged through the chute I . To increase the speed of operation, the ring G is provided with a series of vises to which blanks 95 are supplied by the vibrating holder in succession as they stop opposite the holder.

The construction of the holder.—The holder J , Figs. 2, 20, and 21, is carried by a rock- 100 shaft L , to which is hung loosely a tubular casing j^6 , in which slides a rod j^5 , carrying the head j' , to which the fingers j are secured. The rock-shaft L has arms j^9 , connected by links j^{17} to the head j' , so that when the latter is carried against a stop j^2 , dotted lines, 105 Fig. 20, and the shaft continues to turn the head j' will be elevated to carry the blank upward between the jaws of the vise. The rod j^5 is surrounded by a spring j^7 within the casing j^6 and bearing on a nut or head j^8 at 110 the end of the rod, so as to carry the rod and its head downward as the shaft L rocks in the opposite direction. A finger k is pivoted at 30 to the head j' , and when the holder is horizontal occupies a position beyond but below the spring-fingers $j j$ and prevents the shank of the nail from dropping when the head is grasped between the spring-fingers. Preferably the finger k is spring-supported, a 115 forked arm thereof being pivoted to a sleeve 120 k^4 , sliding on a rod k^5 on the head j' and bearing on a spring k' .

The vises.—Each vise, Figs. 3, 18, and 19, is supported by a block Q^2 , secured detach- 125 ably in a radial socket x^3 of the ring D , Fig. 3, and consists of the stationary jaw 31, se- cured in the block Q^2 , and the movable jaw 32, connected by side links $l l$ to the upper end of a lever l' , which bears at l^6 on a part of the block Q^2 as a fulcrum. A bell-crank floating 130 lever l^2 is pivoted at its corner to the lower end of the lever l' and is provided at its ends with antifriction-rolls $l^3 l^4$, the former bearing on the inclined face of the head o of a shaft

35, provided with a washer o' , bearing on a spiral spring p , confined in a recess in the block Q^2 by a screw-plug p' . Spiral springs q q , connected with the pivot of the inner 5 ends of the links and with the block Q^2 , tend to carry the links and with the block Q^2 , to carry the links and jaw 32 outward, so that the vise is then open to receive the blank as it rises. The vise is then closed by a cam-plate h , which rises, bringing an inclined edge 10 to bear on the roller l^4 to swing the lever l^2 from the position shown in dotted lines, Fig. 19, to that shown in full lines. The blank is thus bit with a yielding pressure as the bearing of the roll l^3 on the head o compresses 15 the spring p , as it also carries inward the lower end of the lever l^1 and draws back the links.

The edging-dies.—The edging-dies F^3 may be constructed in different ways, but preferably each is annular or discular, with an annular beveled face and hollow at the center, so that when turned on its axis to a slight extent it presents a new working portion to act on the edge of the blank. The working faces may 25 thus be repeatedly renewed without removing the dies. To facilitate the turning of the dies, the edges may be recessed, as shown in Fig. 15.

As shown in Figs. 13 to 17, the dies are secured by bolts in sockets in the split ends of levers f f , each pivoted at f' to a slide e , a spring f^2 , connecting the levers, tending to separate their lower ends and separate the dies. The dies are brought together by the 30 action of a lever d , the head d' of which is carried up and down between the upper ends of the levers f f . The dies F^3 F^3 which first act on the blank after it is presented by the holder J should have a quicker and more ex- 35 tended movement than the succeeding edging-dies. The head of the lever d therefore carries a cam or wedge block d^2 , with beveled edges, which when carried between rolls d^4 at the upper ends of the levers f f separate 40 them and bring the dies together. The levers f f of the remaining edging-dies are actuated by the toggles d^3 , Figs. 16 and 17, with spherical ends bearing on the socketed ends of set-screws d^5 to secure universal joints and adjustable bearings for said ends. The slides e must be raised as the nail-blanks are carried around by the ring D and must then be lowered to bring the dies on opposite sides of 45 the blanks. This is effected by extending the head of each lever d through a yoke e^3 at the upper end of the slide, so that as the head rises it will first relax the pressure on the levers f f and will then strike the yoke and lift the slide.

50 *The facing-dies.*—The inner die H' , Fig. 10, of each pair of facing-dies is stationary and fits a socket in the stationary cap-piece, which also carries guides for the slides e . The movable facing-die is carried by the short arm of 55 a lever c , pivoted at c^3 to the cap-piece, and the coacting faces of the dies are substantially parallel, so as to reduce the upset por-

tions of the blanks, as before described. The stem of the die H^3 is clamped in a socket in the split end of the lever c , as shown, and the die H' bears on a set-screw h^3 , thus securing desired adjustment, and both dies are cylindrical and the ends of the blanks are presented only below the centers of the dies, so as to secure new operating faces by turning 75 the dies on their axes. If desired, these dies may be recessed or cupped at the center to secure annular working faces.

The beveling-dies.—The beveling-dies are mounted rotatably similar to the facing-dies in levers c , Fig. 12; but the upper edge of the fixed die H^3 is about level with the axis of the movable die H^4 , which is set at an angle to the face of the die H^3 , as shown, so as to bevel the front face of the end of the blank 85 which bears on the rear die or anvil.

The cutters.—There may be any desired number of cutters to remove the surplus material resulting from the elongation of the blanks by the forging action on the faces and 90 edges.

It is of the utmost importance to get rid of the cuttings and prevent them from falling between the operating parts of the mechanism or being jammed into the blanks. We 95 therefore provide one of the cutters with a spring-bearing which permits the cutter to yield in the act of cutting, but which forcibly moves the cutter outward after a piece is cut off, to thereby propel the cutting forcibly outward and away from the parts. Different 100 constructions may be employed to secure this result; but that shown in Figs. 8, 9, and 22 has proved effectual. As shown, there are two cutters R R' , the latter being a curved 105 blade clamped edgewise between two cheeks in a channel a . (Indicated by dotted lines, Figs. 8 and 9.) In Figs. 8 and 9 the framework carrying the cutters R R' and the necessary parts to hold and operate them consists of four parts X' X^2 X^3 X^4 . Of these the part X' is secured to the plate A by the screw-bolt U , which passes through, but does not come in contact with, the part X^2 . X^2 has a 110 foot-piece dovetailed to X' and fitted tight enough on the dovetail so that it will not change its position when the machine is working, but not so tight as to prevent its being moved laterally when desired. This lateral movement is provided for, so that when the 115 cutters become dull in one place they can be moved to a new position. This can be repeated till the whole length of the cutting edges has been used before it is necessary to take out the cutters for resharpening. There is an oblong 120 hole v^3 in the part X^2 , and under and central with this mortise is a hole v^5 through the part X' and extending into the cap-piece A . On one side and central with the oblong hole v^4 is a channel v' , cut into the part X^2 . By inserting 125 a suitably-shaped cam-wrench V in the hole v^4 and channel v' and turning the wrench V to the right or left, as the case requires, the part X^2 is brought to the desired position.

The part X^2 has an upright portion, on which is a dovetail-shaped slideway, to which is fitted the part X^3 . In the top of the part X^2 is fast a stud x^5 , which passes through an overhanging ledge X^6 on X^3 and has a nut above and one below the ledge, by means of which the part X^3 may be raised or lowered and secured in any desired position. At the top X^3 is formed a tongue X^6 , Figs. 9 and 22, and to the part X^3 is fitted the part X^4 , which is secured to X^3 by the two screw-bolts 10 10. The stationary cutter R' is clamped in place in X^4 by the clamping-plate w . The part X^4 is cut out in such a way that when the cutter and clamping-plate are in position a tunnel w' is formed above the cutter. This tunnel is extended in the part X^4 beyond the outer or non-cutting end of the cutter and after passing the studs and nuts which hold the clamp w has a downward turn and connects with the channel a , forming a chute. Through this tunnel and chute the cuttings are discharged from the machine. The moving cutter R is secured in a mortise in the oscillating shaft x' by the set-screw x^2 . The shaft x' has two diameters, and the smaller part is journaled in the main body of the part X^4 , the larger part, which has the mortise holding the cutter, being journaled in a hollow boss y , formed on the side of the part X^4 . A nut and washer on the outer end of the shaft x' keep it in position laterally, but allow it to oscillate freely. The hub y is slotted above and below to allow the cutter to project in either or both directions from its holder, the slots being wide enough to allow the necessary movement of the cutter. The cutter is driven by an irregularly-shaped plate S , which is journaled on the outside of the hollow boss y . From the hub down there is an irregularly-shaped channel y' in the plate S , inclosing the cutter on three sides, the lower end of the channel being considerably wider than the thickness of the cutter, but not so wide as the part above. Forward of the cutter the plate S is formed to the arc of a circle and fits closely to the roof of the tunnel w' , so that it is impossible for a clipping to pass out over the roof of the tunnel and under the plate S . Back of the cutter the plate S is formed to the arc of a circle of larger radius than the part forward of the cutter, so that when the cutting is being done the plate S will be in contact with the cutter at a point nearly directly back of the cutting edge. Just below the hub y and about at a right angle with the general direction of the channel y' is a hole extending from the channel y' outward through the back part of the plate S . In this hole rests a button-headed plunger 2, with its head in contact with the cutter. Back of the head is a coiled spring 3, which is held in place by the hollow screw 4, which also forms a guide for the outer end of the plunger 2. The parts all being in position, the plunger 2, actuated by the spring 3,

keeps the cutter in contact with the plate S at the point 7. As the plate S is oscillated to do the cutting the cutter moves with the plate until it comes in contact with the piece to be cut. The cutter then stops (the spring not being strong enough to do the cutting) till the point 8 of the plate comes in contact with the cutter, which forces it forward, doing the cutting. As soon as the piece is cut off the cutter flies forward, being propelled by the spring 3 and plunger 2, till it strikes the point 7 of the plate S . This quick motion of the cutter and sudden stop against the point 7 causes the piece cut off to be thrown out through the tunnel w' . The plate S is driven by the gear-segment on the lever b , meshing with the gear-segment on the plate.

Although we much prefer a blank with a surplus of stock, we do not limit our invention to the finishing of nails which have an excess of stock to be cut off during the process of forming the point, as we have found the machine equally well adapted to finishing nails which are forged with just enough stock to form the point. When the machine is used in this way, the cutters are removed. The dies of the first pair may be made without any sink and are so formed that when closed they present a V-shaped opening to the unfinished point of the nail as it is thrust up through the vise. The cam d^3 , which closes the first pair of dies, is made longer, so that the dies are closed before the point of the nail reaches them. By this means a gage is provided which stops the point at the right height and centers it laterally.

Actuating mechanism.—The parts above described may be actuated through the medium of different appliances. We will now describe those which have proved effective. The holder-actuating mechanism is mainly illustrated in Fig. 7, which shows the shaft L provided with a pinion h^3 , engaging a rack on an arm h^6 of a lever, the other arm h' of which bears on an operating-cam H on the driving-shaft H^5 . A spring h^7 tends to rock the lever $h' h^6$ in the direction of its arrow.

The mechanism for actuating the levers b c d is best shown in Figs. 2, 4, 5, 6, and 8 and consists of a vertically-reciprocating head J^5 , carrying two spools C B , between the flanges of which extend the inner ends of the levers b c d , so that the latter are rocked as the head and its spools rise and fall. The head is connected to a bent arm J^4 , having a guide-pin j^{10} at the lower end sliding in a recess in a cross-piece J^3 of the frame, and upon the driving-shaft H^5 are eccentrics j^{12} , the straps of which are connected with arms J^2 , pivoted at their upper ends to a pin j^{13} , connected with the head J^5 , so that the latter is raised and falls on the rotation of the driving-shaft. The spools are adjustable on the head J^5 , being internally threaded to fit a threaded boss 50, projecting from the head, and this boss is split and has an internal

threaded opening to receive two tapering screws K and M, by means of which the boss may be expanded to bind the spools after adjustment. The head J⁵ carries the cam-plate 5 h, which operates the vises. (See Fig. 6.) The turret or ring D turns on an annular supporting-plate E, secured to the frame of the machine, having an annular flange g, radial arms g', which carry a sleeve g'', having at 10 the top a flange g³, to which is bolted the cap-piece A. The cams i i' are placed, as shown in Fig. 5, to act on the lower end of the lever i², which actuates the vises. The cam i' opens each vise as the lever l² thereof is carried past the cam, while the cam i prevents the end of the lever from being thrown too 15 far outward.

The intermittent movement of the turret and the locking of it during the intervals of 20 rest are accomplished as follows: A lever N, carrying a roll r and a detent s, is hinged or journalled at one end to the plate O, which is bolted to the flange g. The plate O has a pend- 25 ent from and integral with it vertical and horizontal bearings carrying the shaft and necessary gearing to drive the vertical shaft carrying the cam P, against which the roll r rests. The lever N is extended beyond the roll r and has attached a spring r', which 30 tends to keep the roll in contact with the cam. Fixed in the cam is a pin which carries a roll Q. The turret projects beyond its supporting-slideway and has on its under side a number of radial grooves or channels t t 35 (shown in dotted lines, Fig. 3,) equal in number to the vises in the turret. In Fig. 3 of the drawings the turret is shown locked by the detent s. The cam P revolves in the direction indicated by the arrow, and just as 40 the detent is being withdrawn from one channel the roll Q is entering the next one, and while the cam revolves one-half a revolution the turret is carried one step forward, and as the roll emerges from the channel the detent 45 enters another channel, locking the turret as before. The cam is so shaped and timed that the turret is always under control either of the roll or detent and cannot become displaced or get out of time with the other parts 50 of the machine.

Without limiting ourselves to the constructions and details shown, we claim as our invention—

1. In a nail-pointing machine, the combination of series of alternating edging and series of facing pressure-dies, means for presenting the point of the blank in succession, first to edging-dies and then to facing-dies and so on alternately, and means for reciprocating said dies to forge the blank to a tapering shape laterally while avoiding reduction in the thickness thereof, substantially as described.

2. In a nail-pointing machine, the combination of alternating edging and facing pressure-dies with cutters at intervals, and means for reciprocating said dies and for pre-

senting the blank thereto in succession to forge the blank to a tapering shape, substantially as described.

3. The combination of a series of pairs of pressure nail-pointing dies adapted to indent the edges of a nail-blank, alternating facing-dies to reduce the upset part of the blank, and beveling-dies coöperating with edging-dies to forge the blank to a point, and means for reciprocating said dies substantially as described.

4. The combination in a nail-pointing machine, of a series of pairs of dies adapted to indent the edges of a nail-blank, alternating facing-dies to reduce the upset part of the blank, and beveling-dies coöperating with edging-dies to forge the blank to a point with cutters at intervals, and means for reciprocating said dies substantially as described.

5. The combination in a nail-pointing machine, of series of pairs of facing-dies and a series of pairs of beveling-dies, edging-dies alternating the facing-dies and beveling-dies, and means for presenting a blank in succession thereto and for reciprocating said dies, substantially as described.

6. The combination in a nail-pointing machine, of series of pairs of facing-dies and series of beveling-dies, edging-dies alternating the other dies, means for presenting a blank in succession thereto, means for reciprocating the dies, and cutters for shearing off the surplus end portion of the blank, substantially as described.

7. The combination in a nail-pointing machine of series of pairs of facing and beveling dies and edging pressure-dies intermediate the pairs of facing and beveling dies, means for reciprocating the same, vises supported by a rotary arm, means for rotating the turret intermittently, and means for operating the dies while the turret is at rest, substantially as described.

8. The combination with the rotating turret and its vises, of a cap-plate, a series of slides sliding vertically in guides of said plate, and edging-dies supported by said slides, with means for rotating the turret intermittently, and for operating the dies, substantially as described.

9. The combination with the rotating turret and its vises, of a cap-plate, a series of slides sliding vertically in guides of said plate, and edging-dies supported by said slides, a series of facing-dies and beveling-dies arranged between the edging-dies, with means for rotating the turret intermittently, and for operating the dies, substantially as described.

10. The combination with the rotating turret and its vises, of a cap-plate, a series of slides sliding vertically in guides of said plate, and edging-dies supported by said slides, cutters and a series of facing-dies and beveling-dies arranged between the edging-dies, with means for rotating the turret intermittently, and for operating the dies and cutter, substantially as described.

11. The combination with the levers supporting the edging-dies, of a reciprocating head and toggles between the head and levers, and adjustable bearings for the ends of the 5 toggles, substantially as described.

12. The combination with the levers supporting the edging-dies, of a reciprocating head and toggles having end ball-bearings between the head and levers, substantially as 10 described.

13. The combination with the levers supporting the edging-dies, of a reciprocating head and toggles having adjustable end ball-bearings between the head and levers, substantially 15 as described.

14. The combination in a nail-pointing machine with means for holding the nail-blanks and for moving them step by step to different positions, of edging pressure-dies supported 20 by vertically-moving slides, substantially as described.

15. The combination in a nail-pointing machine with means for holding the nail-blanks and for moving them step by step to different 25 positions, of edging-dies supported by vertically-moving slides and alternate facing-dies, substantially as described.

16. The combination in a nail-pointing ma-

chine with edging pressure-dies on vertically-movable supports, of facing-dies between the 30 edging-dies, and a turret provided with vises for holding blanks in a position to travel between the facing-dies, substantially as described.

17. The combination with the dies arranged 35 in a circle to operate on blanks carried in a circular course, of radial levers to operate the dies, and a central vertically-reciprocating head to operate the levers, substantially as described.

18. The combination with a rotating turret carrying a series of vises, means for opening and closing each vise as it reaches a position to receive a blank to clamp the latter in a fixed position to the turret, and as it completes 45 its rotation to discharge the blanks, and pressure-dies for operating on the points of the blanks, substantially as described.

Signed by us at New Brighton, Pennsylvania, this 13th day of June, 1899.
